UNITED STATES PATENT OFFICE.

CLINTON F. RANDALL, OF ANDERSON, INDIANA, ASSIGNOR TO ANDERSON FOUNDRY & MACHINE COMPANY, OF ANDERSON, INDIANA, A CORPORATION.

INTERNAL-COMBUSTION ENGINE.

Application filed February 14, 1921. Serial No. 444,824.

To all whom it may concern:

Be it known that I, CLINTON F. RANDALL, a citizen of the United States, and a resident of Anderson, county of Madison, and State of Indiana, have invented a certain new and useful Internal-Combustion Engine; and I do hereby declare that the following is a full, clear, and exact description thereof, reference being had to the accompanying drawings, in which like numerals refer to like parts.

This invention relates to internal combustion engines of the semi-Diesel type wherein the fuel is ignited by auxiliary means when the engine is started and is self-ignited during normal running operations, said fuel being admitted under relative low compression pressure, whereas the Diesel type of engine admits fuel under compression pressures of several hundreds pounds per square inch.

The chief object of this invention is to provide an internal combustion engine of the character described with improved fuel supplying means, which means is adapted to be movable selectively into a plurality of positions for discharging the fuel supplied into a plurality of directions warranted by the condition of operation of the engine.

Another object of the invention is to improve the construction of the fuel supplying means, whereby the fuel line may be drained of air, and whereby the source of pressure and fuel supplying means communicating therewith and with the engine is relieved from the explosion or ignition pressure of the engine.

The chief feature of the invention consists in providing an internal combustion engine of the character described with a movable fuel supply nozzle.

Another feature of the invention consists in the details of construction of the unitary fuel supplying nozzle, and its support upon an internal combustion engine.

The full nature of this invention will be understood from the accompanying drawings and the following description and claims.

In the drawings Fig. 1 is a central sectional view of the cylinder head, combustion chamber and fuel supplying nozzle and igniting means embodying the features of the invention. Fig. 2 is a substantially similar view but is taken at right angles to the

view shown in Fig. 1 and on line 2—2 thereof. Figs. 1 and 2 illustrate a horizontally positioned fuel supplying nozzle. Fig. 3 is an enlarged central sectional view of the fuel supplying means and is taken on the line 2—2 of Fig. 1. Fig. 4 is a vertical sectional view of a modified form of the invention herein termed the vertical type to distinguish the same from the horizontal type shown in Figs. 1 to 3 inclusive. Fig. 5 is a transverse sectional view taken on the line 5—5 of Fig. 4. Fig. 6 is an enlarged central sectional view of the fuel supplying nozzle shown in Fig. 4. Fig. 7 is an enlarged sectional view of the nozzle embodying the invention and a modified mounting therefor and is substantially similar to Fig. 3.

In internal combustion engines of the Diesel and semi-Diesel type the fuel used may be a solid or a liquid, such as powdered coal, crude oil or other suitable material, or a combination of both. The fuel is usually supplied under pressure to the engine cylinder and is ignited therein by the heat generated by the compression of the fresh charge of air together with the heat retained in the walls of the cylinder and the piston from previous explosions. Thus, the impinging of the fuel upon the piston head or some other heated surface of the engine serves to ignite the fuel charge, which causes the generation of gas, the combustion and expansion of which in turn moves the piston to develop power. In the straight Diesel type of engine the fuel has been supplied under high pressures such that the discharge of the fuel into the compressed air instantaneously ignites the fuel. In engines of the semi-Diesel type lower pressures are used, and as a result auxiliary igniting means are provided which are used in starting the engine.

Heretofore it has been customary to provide an opening in an engine cylinder of the semi-Diesel type and secure an auxiliary combustion chamber adjacent said opening, which chamber communicates through the opening with the cylinder. Suitable firing means or ignition means is provided in the auxiliary heating chamber and suitable fuel supplying means is also positioned therein. In the prior art it has been customary to provide deflecting means for deflecting the discharging fuel into a plurality of positions so that in starting the fuel will im-

pinge upon the auxiliary ignition means in the chamber, be ignited and start the engine. After the engine has run for a short time and the cylinder walls and piston have been heated the deflecting means is moved into position such that the discharging fuel will impinge upon either a portion of the cylinder adjacent the opening or will impinge directly upon the piston. The heat of the piston or cylinder will ignite the fuel and cause the engine to run and generate power in the usual manner.

In the construction hereinbefore described the deflecting means associated with the fuel discharging means, after some use, sometimes becomes detached from its support and this usually interferes with the operation of the engine. Also when separate deflecting means is associated with the fuel nozzle, unskilled attendants have failed to move the deflecting means from the starting position to the running position as hereinbefore described, which has resulted in a decrease of power generated by the engine. This invention, therefore, seeks to provide means which obviates these objections and which provides a unitary fuel supplying construction of simple and economical construction.

In Figs. 1, 2 and 3 of the drawings 10 indicates the usual water jacketed cylinder, 11 the piston therin provided with an irregular piston head 111. The cylinder is closed by a water jacketed head 110 which head is complementarily formed to receive the irregular shaped piston head with a minimum clearance volume therebetween when the piston head is in its extreme position. The cylinder head 110 is provided with a neck having a restricted opening 12 therethrough which communicates with the engine cylinder 10 and also with a chamber which is herein termed the auxiliary combustion chamber 13. The chamber 13 is formed by means of a water jacketed head or cover 14 associated with the cylinder head 110. The auxiliary combustion chamber 13 is elongated but somewhat spherical in shape, and a portion thereof is not water jacketed, thereby providing a heated portion of the walls of the cylinder construction. In the non-jacketed portion of the cylinder head there is positioned suitable auxiliary firing or ignition means, while adjacent thereto is positioned a fuel discharging or supplying nozzle which discharges through the recess or cavity 15 in the head or cover 14. Said head or cover and cylinder head are suitably secured together and to the engine cylinder in any desired manner.

In Figs. 1 and 2 a plurality of auxiliary ignition devices is illustrated. The left hand ignition device 16 see Fig. 1, is hollow and has a threaded connection 17 with

the non-jacketed portion of the cylinder head. From said figure it will be noted that the auxiliary firing pin or plug has a portion exposedly positioned, and in the present invention any suitable means may be provided to heat said firing plug such that when fuel impinges thereon the latter will become ignited. Such suitable means may be electrical heating means or may be suitable torch means, such as a plumber's torch or welding torch. In order to convey the heat from the external heating means hereinbefore suggested to the hot spot within the auxiliary combustion chamber, said plug, as stated, is hollowed out. For the same reason that the hollow plug is better adapted to convey heat from the exterior of the combustion chamber to the inner surface thereof, it will be readily understood that said plug is also adapted, when the external heating means is removed, to convey heat from the interior of the chamber to the outside. Thus, if it were desired to run the engine at light loads or under no load, the auxiliary ignition plug 16 would be relatively cool compared with the adjacent portion of the auxiliary combustion chamber. Since under normal running operation the fuel impinges upon the piston by passing through the restricted opening 12, sufficient heat will be generated therein to ignite said fuel, as before described, and said heat will also be retained by another auxiliary ignition device such as the plug 18, which preferably is solid in construction and provided with a beveled face 19. This plug also is positioned in the non-jacketed portion of the cylinder head 10 and is of such material that it will retain the heat and be of relatively low heat conducting quality. Therefore, under light loads or no loads when the heat generated by the engine decreases and the walls of the cylinder and the piston cool down, the auxiliary plug 18 will still remain heated and, therefore, if the fuel impinges thereon positive ignition of the fuel is provided. It will be understood from the foregoing that, as illustrated, the ignition plug 16 will be relatively cooler than the surrounding supporting chamber wall and, therefore, if fuel were to impinge upon said plug under light or no load conditions the same would condense thereon and fail to ignite or else improperly ignite. Thus, a plurality of firing plugs are provided for the reasons indicated. However, it is contemplated that a firing plug which is a modification of the firing plugs 18 and 16 may also be used, and when so used said single plug may be constructed as a solid plug in which may be positioned an enclosed electrical heating element. Thus, in starting said enclosed electrical heating element could be energized to start the engine in the usual manner. After said engine has acquired the normal running op-

eration, said heating device can be de-energized and the firing plug heated in the manner hereinbefore described with reference to the auxiliary plug 18. However, the plural plug construction is but one feature of the foregoing invention and the single combination plug as indicated herein is another feature not claimed in this application, since in many instances electrical energy would 10 not be available where an engine of the character indicated is used.

The chief feature of the invention consists in the fuel supplying nozzle being relatively movable in the head cover 14 so that the 15 fuel stream will be impingeable upon either of the firing plugs shown or upon the piston for the desired operating conditions, such as starting, running and no load or light load. Before proceeding to a detailed 20 description of the movably mounted fuel discharging nozzle it will be noted from Fig. 2 that the head 14 is provided with a suitable opening 20 and communicating with said opening in the present instance is a duct 25 or passage 21 which is adapted to be connected a pressure supplying fuel conduit 22. Said connection consists of a nipple 23 and T-fitting 24. The other branch of the T is connected to a pet cock or relief valve 25 30 which is positioned at the highest point in the combination from the engine to the cylinder so that air which accumulates in the line and cylinder can be discharged at this point by opening the valve and allowing the 35 air to discharge until nothing but oil starts to flow from said valve. Thus, the line may be easily bled and relieved from air bubbles et cetera.

Reference will now be had particularly to 40 Fig. 3 and in said figure a shank 30 of a unitary fuel supplying nozzle is illustrated. The shank 30 is centrally recessed at 31 and the exterior end of said recess is threaded at 32. Adjacent the head of the recess is a 45 plurality of radially extending ports or channels 33 which communicate with an annular channel 34 formed in the outer surface of the shank 30. The annular channel 34 is adapted to register with the duct 21 and thus 50 supply fuel from the duct to the chamber or opening 31. The threaded end 32 of the shank 30 is adapted to receive a valve supporting guide 35 which is centrally apertured at 36. The central aperture is enlarged at 37 and is provided with a tapering seat 38 therebetween. The opposite end of 55 the valve guide 35 is interiorly threaded and positioned therein is a plug or cap 39 having a central channel 40 which, however, terminates short of the end thereof. Extending angularly of said central channel 40 and, 60 preferably in this modification, at right angles thereto is another channel 41 having a restricted orifice 42 therein. The cap or 65 plug 39, as shown in Fig. 3, is seatable in the

recess or cavity 15 and is adapted to discharge fuel into a plurality of directions when said cap is rotated or moved into said directions. Slidably supported within the central opening 36 is a valve stem 43 carrying a head 44 with a tapered portion 45 therebetween. The stem 43 is elongated and extends through the guide 35 and upon its free end in the chamber or recess 31 is secured a washer 46 by means of a pin 47. Between the washer 46 and the guide 35 is a light spring 48 which serves to seat the valve 45 on the seat 38 when the pressure in the auxiliary chamber 13 equals that of the fluid supplying pressure in the conduit 23. 70

The means for supporting the unitary nozzle hereinbefore described includes the opening or channel 20 in the cover portion 14 and a stuffing box comprising a cap 50, 75 and packing 51, said cap being suitably secured to said cover 14. The unitary valve shank 30 is provided with an outwardly extending portion 53 to which is secured a suitable handle means 54, preferably in the form of a lever. Said handle means is provided with a socket 55 and in said socket is a tooth or detent 56, the outward movement thereof being limited by a head portion 57, 80 said movement being caused by a spring 58 retained in said socket by means of a cap 59. Preferably integral with the cap 50 is an arcuate ridge 59 provided with a series of radial notches or grooves 60 into which the detent 56 is seatable to yieldingly maintain the handle in a pre-determined position. Thus, the handle 54 may be readily moved from one position to another as indicated by the grooves or slots 60, which positions are indicated in Fig. 1 by the dotted lines showing the discharge of the fuel into a plurality of directions. 85

In Figs. 4 to 6 inclusive the invention is 90 illustrated when the nozzle is not positioned in a horizontal plane. The only differences between the construction shown in Figs. 4 to 6 inclusive and that shown in Figs. 1 to 3, 95 consist in the positioning of the plural firing plugs adjacent each other and positioning the nozzle in angular relation to the perpendicular and horizontal with the following additional changes. The relief valve 25, 100 see Fig. 2, associated with the conduit 22 in said figure is herein shown directly connected with the unitary nozzle. While the other change consists in the channels 40 and 41 terminating in the orifice 42, as shown in Fig. 3 extending angularly of the cap or tip. The same reference numbers will indicate the identical parts in the modification shown in Figs. 4, 5 and 6 and the numbers for similar parts, although differently positioned, will bear the usual reference numbers increased by one hundred. 105

In this modification of the invention the 110

unitary nozzle is associated with the two auxiliary ignition devices 116 and 118 positioned as shown in Figs. 4 and 5. This is possible by the substitution of the tip or 5 cap 139 provided with the channel 140 and orifice 142. The channel 140 extends angularly of the central channel or axis of the nozzle, and terminates in the orifice 142 communicating therewith, which is adapted to 10 be centrally positioned with the vertical axis of the engine cylinder in one position. Similarly the duct 121 and the head 114 is angularly positioned, as is also the supplying conduit 123. Instead of the relief valve 15 25 being associated with the conduit 23, in the present instance the relief valve 125 is associated with the conduit 123 through the fuel supplying nozzle by said nozzle having a central channel 150 therein which communicates with the pet cock or relief valve 125, since this is the highest point of the fuel supplying system included in the engine. While the invention has been described with 20 relation to two types of vertical cylinders 25 the same may be readily adapted to engine cylinders positioned at other angles or horizontally, the necessary changes being the positioning of the unitary fuel supplying nozzle at the requisite angle and the positioning 30 of the discharge orifice in the top at the requisite angle.

In the modification illustrated in Fig. 7, the generic features of the invention are retained, yet the particular mounting of the 35 valve and the detailed construction of the valve are somewhat modified. In Fig. 7 it will be noted that the shank 230 is provided with the central chamber 231 and communicating therewith is a central channel 250. 40 However, in the present instance instead of the fuel being supplied to the central chamber 231 by an annular channel adjacent thereto and a duct communicating with said channel, the fuel is supplied through the 45 central channel or passage 250. As shown clearly in Figs. 4, 6 and 7 the shank portion 230 is provided with a tapered forward portion or face 220 and the opening 20 in the closure member 14 is similarly provided 50 with a complementary tapered seat.

The nozzle is substantially similar to that hereinbefore described but differs therefrom as follows. Upon the forward end of the shank 230 is provided a chamber 231 which 55 is an enlargement of the central channel 250 and the outer portion of said enlargement 231 is threaded to receive the threaded portion of a tip 339. The tip 339 is provided with an angular channel 340 which communicates with a discharge orifice 342. Said channel 340 is provided with an outlet 341 which communicates with the chamber 231. It will be noted from Fig. 7 that the cut-away portion or channel 341 is at the highest 60 point of the nozzle construction and,

therefore, air which is present in the oil and fuel supplied will collect at this point and will be discharged into the cylinder of the engine. It is to be here noted that the inner nozzle is slightly inclined to the horizontal and is rotatable about said inclined axis. 70

The check valve means, in the present modification, comprises a head portion 344 and an elongated stem portion 343 with an intermediate tapered face 345 seated upon a similar indicated face on the shank 230. The stem 343 is of less cross sectional area than the central channel 250 and, therefore, fuel will pass through said channel along 80 said stem. The outer end of the channel 250 in the free end 253 of the shank is enlarged at 349 and the faces of said enlargement constitutes a seat for one end of the coil spring 348 concentric with and carried by the valve 85 stem 343. The other end of said spring is adjustably secured upon said valve stem by means of the adjusting cap 346 and the securing pin 347.

The closure member is closed by a bonnet, 90 plate or cap 249 which is provided with a pilot flange 248, seatable in an enlargement of the opening 20 in the closure member 14. The cap or bonnet 249 is suitably secured to the closure member, as by means of the 95 bolts 247. The bonnet 249 is provided with an overhanging arm 246 which forms a bearing 245 in alignment with the opening 20, when said bonnet is associated with the closure member. A set screw 244, having 100 a threaded exterior, is supported in the bearing 245, said bearing being also threaded. The set screw 244 and the free end 253 of the shank 230 are provided with complementary tapered rounded seats herein indicated by the numeral 243, and said complementary seats engage each other when the set screw is threaded into the opening of the bearing 245 and, therefore, forms a fluid tight joint between said set screw and the shank. Thus, a fluid tight joint will be 105 provided between the several bearing surfaces such that the nozzle will be supported in the closure member in an improved manner. 110

In the present modification the set screw 244 is provided with a central channel or passage 242, which central channel or passage is adapted to register with the central channel 250 in the handle engageable portion 253 of the shank 230. A suitable lock nut 241 rigidly secures said set screw in the adjusted position, while upon the other end of said set screw 244 there is associated the usual union construction 240 which is connected with the fluid supplying conduit 22. Thus, fluid may be supplied through the end of the nozzle and longitudinally thereof instead of angularly thereof as hereinbefore illustrated. It will be here noted that the 115 120 125 130

channel 242 is enlarged to receive the cap 346 and valve stem 343.

- While any suitable handle means may be associated with the shank 253 to rotate or move said nozzle into one of the several positions, the following is provided. A split collar 239 is adapted to be received upon the shank 253 and be secured thereto in non-rotatable relation by means of the pin 238 which locks said collar to said shank so that rotational movement of the collar will rotate the shank. The collar is provided with a handle extension 254, whereby the same may be readily grasped by the operator to rotate said collar and, therefore, the shank. Suitable means is provided whereby the handle, or rather the tip, and nozzle will be limited in movement, and herein is illustrated by a stop pin 255.
- While the invention has been described in great detail and some modifications of the generic idea have been disclosed herein or suggested, it will be understood that these modifications, as well as others which will readily suggest themselves to those skilled in the art, are all considered to be within the broad purview of this invention. As for instance, a yoke supported on two studs and maintained in fluid-tight relation with the nozzle at 243 (Fig. 7) by means of two nuts could be substituted for the bracket 249

and still be within the limits of this invention. The foregoing specifications are to be considered illustrative rather than restrictive in character.

35

The invention claimed is:

1. In an internal combustion engine having a cylinder and a piston therein, a fuel supplying nozzle tip, an auxiliary chamber communicating with the engine cylinder, 40 and a plurality of auxiliary ignition devices in said chamber, said nozzle tip being movable into position to direct the fuel discharged therefrom upon said auxiliary ignition devices or said piston.

45

2. In an internal combustion engine having a piston and cylinder provided with an opening therein, the combination of closure means for said opening having an auxiliary firing chamber therein communicating with said cylinder through said opening, a fuel supplying tip in said closure means for discharging fuel into said chamber, and a plurality of auxiliary fuel ignition means in said chamber, said tip being movable to direct the discharging fuel upon said auxiliary fuel ignition means or upon said piston.

50

In witness whereof, I have hereunto affixed my signature.

CLINTON F. RANDALL.
